UNITED STATES PATENT OFFICE.

JULIUS E. MERRIMAN, OF MERIDEN, CONNECTICUT, ASSIGNOR TO FOSTER,
MERRIAM & CO., OF SAME PLACE.

HANDLE.

SPECIFICATION forming part of Letters Patent No. 271,095, dated January 23, 1883.

Application filed June 9, 1882. (No model.)

To all whom it may concern:

Be it known that I, JULIUS E. MERRIMAN, of Meriden, in the county of New Haven, in the State of Connecticut, a citizen of the United States, have invented a new and useful Improvement in Drawer-Pulls, of which the following is a full, clear, and exact description, reference being had to the accompanying drawings, forming a part of this specification, in explaining its nature, in which—

Figure 1 is a perspective view of a drawer-pull illustrating my invention. Fig. 2 is a horizontal section thereof, illustrating the construction. Fig. 3 is a front elevation, representing a bail-handle instead of a ring-handle; and Fig. 4 is a detail view, illustrating the construction shown in Fig. 3.

This invention is an improvement upon that described in my Letters Patent No. 178,317, dated June 6, 1876. In said Letters Patent I describe a drawer-pull having a tubular shank struck up from one and the same piece of metal, and having a socket at its outer end for the reception of the ball of the handle or pull; and I am aware that it is not new to make an open-ended tubular standard or a tubular standard of uniform diameter throughout, or to use for a standard a metal shell held in place by a screw.

The principal points of my present invention are comprised in the hollow drawer-pull standard, having a shank and enlarged head and cap formed to cover and fit closely over the head, and means provided whereby the segmental ring or other suitable handle is united to the standard, the construction concealing the ends of the ring and preventing it from turning in the standard, aided by a filling inside the head of the standard, and the whole thus formed thereby given an appearance of strength and solidity.

The simplicity of my present adaptation of parts promotes cheapness without sacrificing beauty or practical utility.

Referring to the drawings, *a* is a tubular head, and *b* its shank. *c* is a cap, which fits tightly upon the head and extends to the point *d*, in order that it may appear to be solid with the head. By this construction the ring is prevented from being turned in the head upon its own center and its ends serve to fasten the cap and head securely together. The segmental ring *e* is preferably used, whose ends pass through the cap and head and inside the wood or other filling *g*, placed in the cavity *f*, the foregoing parts being provided with holes *h*, to receive the ends *m m* of the ring. If the bail-handle, as represented in Fig. 3, is used, there would of course be but one hole *h* in the cap and head.

One of the chief objects of my invention is to cheapen the construction without sacrificing the apparent solidity and beauty of the structure.

Having thus fully described my invention, I claim and desire to secure by Letters Patent of the United States—

The hollow drawer-pull standard consisting of the shank *b*, an enlarged head, *a*, the cap *c*, and the filling *g*, the head, cap, and filling each provided with holes *h*, in combination with the open or segmental ring *e*, or other handle, adapted to be united with the standard at the holes *h*, all arranged and constructed substantially as and for the purposes set forth.

JULIUS E. MERRIMAN.
